FOR SMOKING TOBACCO.

PATENTED
OCT 9 1866

Des. 2488

John W. Carroll of Lynchburg, Va.
Letter's Patent No. 2488, dated Oct. 9, 1866.
Design for a Trade Mark.

The Schedule referred to in these Letters Patent and making part of the same.

To all whom it may concern:

Be it known that I, John W. Carroll of the City of Lynchburg, County of Campbell and State of Virginia have originated and designed a new Design for a Trade Mark or Brand to be put upon Smoking Tobacco, of which the accompanying drawing marked A, is a full, clear and exact copy and representation the same being made a part of this specification.

What I claim as my invention and desire to secure by Letters Patent is,
The Design for a Trade Mark or Brand for Smoking Tobacco herein set forth and shown
